UNITED STATES PATENT OFFICE.

PAULUS HEÝLANDT, OF ERFURT, GERMANY.

STORAGE VESSEL FOR LIQUEFIED GASES.

No. 797,577.

Specification of Letters Patent.

Patented Aug. 22, 1905.

Application filed April 20, 1904. Serial No. 204,130.

To all whom it may concern:

Be it known that I, PAULUS HEÝLANDT, a citizen of the Empire of Germany, residing at Erfurt, in the Kingdom of Prussia, Empire of Germany, have invented a new and useful Storage Vessel for Liquefied Gases, of which the following is a specification.

My invention relates to improvements in storage vessels for liquefied gases—such as air, oxygen, nitrogen, &c.—whereby these storage vessels are enabled to preserve the liquefied gases for a longer time than hitherto, and they are also rendered more durable and even capable of withstanding the strains on a transport either by rail or by mail-carriage without being damaged or losing their contents by vaporization. The hitherto-known metal storage vessels used for this purpose failed to give every satisfaction, chiefly by reason of the vaporization of the liquefied gases for want of good insulation. The glass bottles are too liable to break easily, and their transport is in certain countries only permitted when accompanied by a man. There are also metal storage vessels comprising external and internal vessels, so that spaces of a nearly uniform thickness are formed between them and from which the air has been pumped out, so as to reduce the transmission of heat from without to the internal vessels by means of the rarefied air. Experience, however, has shown that the temperature of the ambient air transmitted to the liquefied gases by the conduction of the necks and the walls of the internal vessels contributes to the vaporization of the gases. There are also storage vessels of this kind in which the internal vessels or the storage vessels proper are made of wood—i. e., a heat-non-conducting material—but such wooden vessels are tightened and strengthened by hoops of iron or metal—i. e., a heat-conducting material. Trials have proved such storage vessels to be incapable of preserving the liquefied gases for a considerable time.

The storage vessels comprising external and internal vessels are according to my invention so improved as to combine the durability of the known metal storage vessels and the good properties of the known glass bottles and that they can be transported safely either by rail or by mail-carriage.

The objects of my improvement are, first, to provide the preferably ball-like internal vessel with a narrow vertical neck and to make both the internal vessel and the neck of a heat-non-

conducting material; second, to make the external vessel of metal or enameled metal and to provide it with a dome which surrounds the narrow neck and is connected therewith; third, to provide a ball-like protecting-casing for inclosing the external vessel, and, fourth, to provide means for automatically bringing the neck of the internal vessel into the vertical position during any inclination of the protecting-casing. I attain these objects by the construction illustrated in the accompanying drawings, in which—

Figure 1 shows a vertical central section through a ball-like storage vessel, a ball-like protecting-casing, and a device for holding the neck in its vertical position, while Fig. 2 is a vertical section, on an enlarged scale, through the upper part of the storage vessel.

The storage vessel shown comprises an internal vessel *a*, of heat-non-conducting material, for containing the liquefied gas and an external vessel *b*, of metal, and is inclosed in a protecting-casing *m*. The neck *u* is made in one piece with the internal vessel *a* and diverges upward. An annular piece *c*, of lead or other metal or an alloy, is secured in any known manner on the upper edge of the neck *u*, and another piece *v* of a similar material and provided with an internal screw-thread, Fig. 2, is secured within the neck *u*. Both pieces *c* and *v* are rigidly connected by soldering at *w* or otherwise. The internal piece *v* serves for receiving a plug *n* with a spring-pressed safety-valve *e*. The annular piece *c* may be formed by casting on the neck, or it may be cast separately and fit loosely on the upper edge of the neck *u*, so that the space between them requires to be filled up with a suitable composition for rigidly connecting the parts. The external vessel *b* is provided with a dome *q*, which is soldered on the pieces *c* and *v*. Thereby the two vessels *a* and *b* are connected with each other. They are preferably made ball-like in order to better resist the internal pressure on the walls of the internal vessel and the external pressure of the atmosphere on the external vessel. Between the two vessels a space *r* of preferably uniform thickness is left, from which the air is pumped out in any known manner through a narrow tube *i* of lead or the like, and afterward this tube *i* is closed by bending and soldering. As the internal vessel *a* is sufficiently strong it need not be secured at the bottom on the external vessel *b*. For reasons to be hereinafter explained it is only neces-

sary to hold the neck u and the dome q in the vertical position shown. For this purpose a weight z , of lead or other heavy material, is secured on the lower half of the external vessel b and made to rest on three or four small balls $k' k'$, which run on the internal wall of the ball-like protecting-casing m and engage in suitable recesses of the weight z . On the upper half of the external vessel b are fastened several (here four) tubes $g' g$ at equal distances from each other, and in these tubes are secured, by means of set-screws $h' h$, adjustable bearings $f' f$ for small balls $k' k$, which latter run on the internal wall of the protecting-casing m . The two vessels a and b and the parts thereon are so proportioned as to place their center of gravity 2 at a sufficient distance beneath the center 1 of the protecting-casing m that the whole will readily adjust itself and bring the neck u and the dome q into the vertical position should the protecting-casing m be inclined by chance. The protecting-casing m is preferably made in halves, which are hinged to each other at l and can be opened and closed at the other side by means of a double screw o , engaging in lugs $l' l'$. The lower half of the casing m is preferably provided with a foot d at the bottom and with a plurality of small perforations $p' p$ at a convenient height. The upper half of the casing m is provided at the top with a ring s , in which a screw-threaded cover t can engage.

This storage vessel is operated as follows: After removing the cover t and the plug n the liquefied gas is in a known manner introduced into the internal vessel a through a tube placed in the neck u , and then the plug and the cover are replaced. As the material of the internal vessel a and the neck u is a bad heat-conductor and the transmission of heat from without through the nearly absolute vacuum in the space r is very slow, it follows that the gas will remain in its liquefied state for a longer time than hitherto. Should at last a certain small quantity of the same have vaporized and a certain small overpressure thereby be produced, the spring-pressed safety-valve e will open and allow the excess of the vaporized gas to escape into the space between the external vessel b and the protecting-casing m . There the gas will expand and produce an intense cold, while it passes downward until it escapes through the perforations $p' p$ to without. Where so preferred, of course the protecting-casing m may be covered with a layer of heat-non-conducting material—such as felt, hay, &c., as indicated by the circle m' —so as to delay as much as possible the vaporization of the liquefied gas. For the same reason the outside of the internal vessel a and its neck u and the inside of the external vessel b and its dome q are preferably brightened or polished in any known manner.

When the liquefied gas is required for use, the cover t and the plug n are removed and a device of any known construction is introduced into the neck u , after which the liquefied gas can be extracted, as usual.

The tubes $g' g$, with the adjustable bearings $f' f$ and the balls $k' k$, may be omitted.

The internal vessel a , and more particularly its neck u , may be made of any heat-non-conducting material—such as, for example, earthenware, celluloid, air-tight papier-mâché, or a composition of non-conducting materials. It is essential that this material be air-tight, sufficiently strong, and not liable to damages from the difference in temperatures—*i. e.*, from the difference between the intense cold of the liquefied gas and the temperature of the ambient air. I have found that porcelain is most suitable for this purpose. It will have to depend upon the material how thick the internal vessel a and its neck u should be made. Celluloid vessels and necks may be made much thinner than paper or earthenware or porcelain vessels and necks.

According to the material the neck u will require to be made more or less thick, so as to support the internal vessel a and to protect it from breaking off under the action of jerks. The annular pieces c and r' may be made of any other material or a composition which renders their fastening on the neck u possible and leads from the non-conducting—*i. e.*, less contracting and expanding—material up to the conducting—*i. e.*, more contracting and expanding—material.

Owing to the very low point of ebullition of most liquefied gases—such as air, oxygen, hydrogen, nitrogen, &c.—a small quantity of the gas will continuously vaporize, and hence a certain pressure will be produced, so that it is not possible to conserve such liquefied gases in perfectly-closed vessels. For this reason it is absolutely necessary that the spring-pressed safety-valve e should always remain at the top to enable the vaporized gas to escape through this valve and to prevent the liquefied gas from flowing off in case the valve is at a point beneath the level. The vaporized gas above the level having a greater specific weight than the ambient air will then be able to check the admission of air. To insure this isolation of the storage vessel by the vaporized gas, and thereby the preservation of the liquefied gas for a longer time, it is necessary to provide means for keeping the neck of the internal vessel and the spring-pressed safety-valve in the vertical position. Such an arrangement has been described above with reference to Fig. 1. The balls $k' k$ may also be replaced by equivalent means. For example, the outside of the weight z may be ground and fitted to slide on the inside of the casing m , while a suitable lubricating material is employed to reduce the friction. The storage vessel so arranged will be able to au-

tomatically retain the vertical position of its neck in spite of accidental inclinations of the protecting-case, so that the vaporized gas is allowed to open the safety-valve and to escape, while a flowing off of the liquefied gas is rendered impossible. The vaporized gas escaping from the safety-valve will expand in the space within the casing *m* and produce an intensive cold before escaping to without through the perforations *p p*, and thus contribute to the preservation of the liquefied gas.

For the transit it may be advisable to place the storage vessel with the protecting-casing in a sheet-case or a basket lined with wood-chips or wood-shavings, hay, &c., to protect the contents from jerks or pressures.

The storage vessel may be varied in many respects without deviating from the spirit of my invention.

What I claim as my invention, and desire to secure by Letters Patent, is—

1. In a storage vessel for liquefied gases, the combination with a ball-like internal vessel of heat-non-conducting material for containing the liquefied gas and having a vertical neck, of two annular pieces of lead or the like secured on the upper edge of said vertical neck one without and the other within, a plug adapted to close the internal of said two annular pieces and thereby said vertical neck, a spring-pressed safety-valve in said plug, a ball-like external vessel of metal inclosing said ball-like internal vessel and having a dome on which said two annular pieces are fastened, so that a space of nearly uniform thickness is left between the two vessels, a narrow tube of lead or the like on said ball-like external vessel and closed by soldering after a vacuum has been formed in said space, a ball-like protecting-casing inclosing said ball-like external vessel and its dome, and means for retaining said vertical neck in its erect position in spite of any accidental inclination of said ball-like protecting-casing.

2. In a storage vessel for liquefied gases, the combination with a ball-like internal vessel of heat-non-conducting material for containing the liquefied gas and having a vertical neck diverging upward, of two annular pieces of lead or the like secured on the upper edge of said vertical neck one without and the other within, a plug adapted to close the internal of said two annular pieces and thereby said vertical neck, a spring-pressed safety-valve in said plug, a ball-like external vessel of metal inclosing said ball-like internal vessel and having a dome on which said two annular pieces

are fastened, so that a space of nearly uniform thickness is left between the two vessels, a narrow tube of lead or the like on said ball-like external vessel and closed by soldering after a vacuum has been formed in said space, a ball-like protecting-casing inclosing said ball-like external vessel and its dome and made in halves, which are hinged together on one side and can be opened and closed on the other side, a weight secured on the bottom of said ball-like external vessel for bringing its center of gravity beneath the center of said ball-like protecting-casing, means for reducing the friction between said weight and the inside of said ball-like protecting-casing, and a foot at the lower half of said ball-like protecting-casing.

3. In a storage vessel for liquefied gases, the combination with a ball-like internal vessel of heat-non-conducting material for containing the liquefied gas and having a vertical neck diverging upward, of two annular pieces of lead or the like secured on the upper edge of said vertical neck one without and the other within, a plug adapted to close the internal of said two annular pieces and thereby said vertical neck, a spring-pressed safety-valve in said plug, a ball-like external vessel of metal inclosing said ball-like internal vessel and having a dome on which said two annular pieces are fastened, so that a space of nearly uniform thickness is left between the two vessels, a narrow tube of lead or the like on said ball-like external vessel and closed by soldering after a vacuum has been formed in said space, a ball-like protecting-casing inclosing said ball-like external vessel and its dome and made in halves which are hinged together on one side and can be opened and closed on the other side, a weight secured on the bottom of said ball-like external vessel for bringing its center of gravity beneath the center of said ball-like protecting-casing, and a plurality of balls engaging in recesses of said weight and adapted to roll on the inside of said ball-like protecting-casing, a plurality of perforations being provided in said ball-like protecting-casing for allowing the vaporized gas discharged from said spring-pressed safety-valve to escape.

The foregoing specification signed this 7th day of April, 1904.

PAULUS HEYLANDT.

In presence of—

HANS VENER,

GUSTAV MÜLLER.
